SLIDE DEVICE FOR DAM FLASHBOARDS

Jean Aubert, Paris, France

Application November 17, 1952, Serial No. 320,885

Claims priority, application France December 20, 1951

3 Claims. (Cl. 61—27)

The invention relates to improvements to flashboards used on river dams, and known as "Aubert" flashboards.

Such dams consist of a row of flashboards H, perpendicular to the current, known in itself, and shown in Fig. 1 with an old form of slide. Each of these flashboards is swivelled on a pivoting stand m, and as the pressure of water endeavors constantly to let it turn downstream, it is held in position by a strut a which bears on their middle part, and terminated by a foot p provided with two parallel cheeks j₁ and j₂, separated by a hollow e. The foot p bears on a slide which essentially comprises a continuous rack c provided with stop-notches, three in number, for example: c₁, c₂, c₃. These notches are restricted by the teeth, d₁, d₂ and d₃.

The foot p is intended to straddle the rack c, the cheeks j₁ and j₂ preventing any lateral movement of the foot when the latter moves along the rack. The foot p can engage in the notches c₁, c₂ and c₃, which fixes three stop positions for the flashboard, I, II, III, in which the nearest to the vertical is I.

If the flashboard is continued to be straightened beyond position I, the foot p reaches a passing position designated by 0, where it is shifted towards the left (for an observer looking from up-stream towards down-stream: in the direction of f). This lateral shifting of the foot is achieved by an inclined plane which conducts it to the up-stream end of a trough g parallel to the rack c. To this end, the joint at k is provided with sufficient play so that the strut can shift slightly laterally. If the flashboard is then lowered, the foot p traverses the trough g in the direction of the current (in the direction of f from up-stream towards down-stream).

The trough g inflects in the vicinity of the down-stream end, and the foot penetrates into a kind of pit G, where it regains the axis of the rack c.

In this position (position IV), the flashboard is completely down.

A slide device of this kind nevertheless has the following disadvantage: it is impossible to lower the flashboard directly in the direction of f, from one notch to the next one (from position I to position III, for example). To carry out such an operation it is actually necessary to describe a kind of loop I—0—IV—III, which involves a loss of time and an appreciable consumption of power. Likewise, to go from position III to position IV, it is necessary to make the loop III—II—I—0—IV.

Furthermore, in spite of its weight, the foot p of the strut may, during these manoeuvres, be shifted to the left or to the right by the current. If it crosses the vertical side which restricts the trough g, a diver's help will be necessary to put it back into the correct position.

The purpose of the present invention is to obviate these disadvantages, and it relates to an industrial product constituted by a slide whose particular shape enables the flashboard to be more easily, more certainly and more speedily moved.

The slide in accordance with the invention comprises a rack completed by some shaped guiding surfaces. The

foot of the strut bears on the rack when the flashboard is fixed in one of the positions I, II or III. When the flashboard is moved up or down, so as it passes from one of the above cited positions to another one, the foot of the strut circulates either on the rack, or on the right, or on the left of it. In addition to this general up-stream or down-stream movement of the foot, which is due to the rotation of the flashboard, the guiding surfaces impell to the same foot small lateral or vertical displacements, whose purpose is to bring at last the said foot into the necessary position, so that the flashboard may be stopped in the desired angular position.

Other features with regard to the shape and arrangement of the guiding surfaces will also be described during the description which follows.

The attached drawings, in addition to Fig. 1 mentioned above, comprise Figures 2 to 9 regarding a particular form of embodiment of slide according to the invention, given by way of example, and without any restrictive character.

More precisely:

Fig. 2 is a view of the top of the slide.

Fig. 3 is lateral elevation view, for an observer situated to the right of the slide, taken in the direction of the current (f direction).

Fig. 4 is a lateral elevation view of the down-stream section of the slide, for an observer situated to the left of the latter.

Fig. 5 is a perspective view of the section, for an observer situated up-stream on its axis and looking down-stream.

Fig. 6 is an elevation view of this section, for an observer situated down-stream, looking up-stream.

Fig. 7 is a simplified diagram of the slide, seen from above, as in Fig. 2.

The Figs. 8 (a, b, c) are sections along the lines VIII_a, VIII_b, and VIII_c of Fig. 7.

Fig. 9 is a perspective view of the slide as seen from down-stream of the flashboard.

The slide shown by way of example in Figs. 2 to 6 is made of two sections: an up-stream section T_m and a down-stream section T_v.

The T_m section comprises a main rib N₁, parallel to the current, arranged in the symmetrical plane of the flashboard and provided with two teeth d₁ and d₂ (Figs. 2 and 3). The T_v section also comprises a main rib N₂, in the extension of N₁ and provided with a tooth d₃. The assembly of the teeth d₁, d₂ and d₃ make the rack of the flashboard. In the utilisation position, the flashboard is motionless and its foot p is locked by one of these teeth, the cheeks j₁ and j₂ of this foot being arranged on either side of the main rib N₁ or N₂, which settles the stopping positions I, II or III of the flashboard, respectively corresponding to d₁, d₂ or d₃.

The rib N₁ of T_m is extended towards up-stream by a guiding surface S₁ situated on the left of T_m and substantially composed of an element of a plane steeply sloped to the right of T_m. After S₁ is an inclined plane S₂, sloping in the same direction as S₁, but with a less steep slope. At the end of this plane are two vertical guiding panels S₃ and S₄, forming an obtuse angle, the panel S₃ being placed at the right of T_m, that is, on the opposite side of S, with respect to the rack.

The surface S₁ is shaped so as to push the foot p of the flashboard by skidding (when it is drawn towards up-stream from d₁) to the right of N₁.

If the foot p continues to be drawn up-stream, the panel S₃ leads that foot towards S₂ and allows it to pass over this surface. The panel S₄ enables p to have a lateral bearing on the right, if it is drawn as far as the passing position 00.

From the down-stream part of T_m, two other vertical panels S₅ and S₆ are placed, respectively situated to the

right and left of N_1 . S_6 is notched in accordance with one part of an inclined plane S_7 , to permit the passage of the cheek j_1 of p when the latter is drawn towards d_2 , straddling N_1 .

The section T_v is more complex than the T_m section. As already explained, it comprises a rib N_2 , separated from N_1 by a certain space i . The rib N_2 is preceded, on the up-stream side, by two associated surfaces shifted to the right; one S_8 , substantially dihedral and forming a rib, the bisector plane of which is vertical but oblique to the rack and placed appreciably in the bisection of N_1 and S_5 . S_8 is intended to be forked by the foot p when it shifts towards down-stream. The outer surface B whose action on the foot p is described hereinafter, essentially comprises the planes S_9 and S_{10} , both sloping to the left, the slope of S_{10} being greater than that of S_9 . The surface B is thus shaped for guiding the foot p towards d_3 by acting on J_2 , when p shifts towards down-stream. The surfaces S_8 and B are connected to N_2 by a kind of dihedral S_{12} , S_{13} , convex upwards. The surface S_{12} is appreciably horizontal, and stopped at a certain height above the floor, as shown in Figs. 4 and 5, whereas the surface S_{13} descends to the floor level (Fig. 6).

The terminal part of N_2 descends in an easy slope into the pit G , flared from up-stream towards down-stream and intended to accommodate the foot p when the flashboard is lowered, even if this foot is appreciably carried along laterally by the current. This pit, of which only a part is shown, is symmetrical in relation to the axis of the ribs N_1 and N_2 .

The movements of the foot p on the slide during the movements of the flashboard can be more easily followed in Fig. 7, where the guiding surfaces are systematised and shown by the plane elements.

The flashboard is presumed originally to be in the down position (position IV, foot p in the pit G). The dotted line shows the track of one point of the cheek j_1 of p . The flashboard being pulled towards up-stream, p whatever its original position in G , is guided by the oblique walls of the latter, so that it forks N_2 and traverses it to d_3 along the track IV—I—III. The tooth d_3 fixes the position III for the flashboard and foot. The flashboard being thus drawn again up-stream (line III—2—3), j_2 comes into contact with S_{13} , then S_{12} , and falls on the floor, escaping from S_{12} . At this moment, j_1 is at 3 and there is the option:

Either to take the flashboard to IV and allowing it to slope down-stream, j_2 then slides against N_2 , j_1 following the line 3—4—IV. At the end of the stroke, the foot p is again at IV, IV indicating in fact any position in the pit G , and the flashboard is down. It has thus been possible to pass directly from position III to position IV.

Or else the flashboard is taken to the position II or I and continued to be drawn up-stream. The foot p , guided by S_8 and S_9 then compulsorily forks N_1 , j_1 being able to pass, due to the slope S_7 (track 3—5—II). If it is not desired to stop the flashboard at II and it is continued to be drawn, p , still straddling N_1 passes d_2 , then reaches d_1 (track II—6—I).

If the flashboard is drawn up-stream from the position I, j_1 comes into contact with S_1 . This surface being very sloping, j_1 skids to the right and arrives at the passage position 0 (track I—8—0).

At 0, there is a fresh option:

Either it is desired to go to IV and the flashboard continues to be drawn up-stream. Then j_2 guided by S_3 leads p to S_2 , or its rises, then falls on the floor to the left of T_m and arrives at the passage position 00 (track 0—10—00). The flashboard then being released down-stream, the foot p descends in the direction of the current, the cheek j_2 bearing, if possible, on S_4 , then on the vertical walls of S_2 and S_1 , and on the left part of N_1 (track 00—11—12—13).

When j_2 comes against the vertical wall of S_7 , the foot p is shifted to the left, this movement being accentuated by the guiding surface S_5 . Thanks to this surface, p passes to the left of 3 (track 14—15—16), then finally falls into the pit G , thus returning to IV (track 17—IV). Thus, it has been possible to pass from position I to position IV.

Or else, if it is desired to go directly from I to III, the foot p being always presumed at 0, on leaving the position I, the flashboard is allowed to lean down-stream p then descends in the direction of the current, j_1 bearing on the right part of N_1 (track 0—18—19).

When j_1 is at 19, j_2 comes into contact with S_5 which plays the part of guide concurrently with the terminal part of N_1 and conducts the notch e of p right opposite S_8 . The foot p then forks S_8 (track 19—20 and Fig. 8a). p rises little by little, while j_2 comes into contact with S_9 (Fig. 8b). At this moment, p distinctly dominates the part of the rib N_2 situated up-stream from d_3 . S_8 then moves j_2 and consequently p to the left until e is above N_2 . Then j_2 comes into contact with S_{10} with p at a steep slope (Fig. 8c). As at this time p does not fork S_8 any more, from which it has just escaped, j_2 skids and p straddles N_2 , slightly upstream from d_3 . These operations take place on the track 20—21—III.

The arrangement adopted for the various guiding surfaces encountered has thus made it possible to pass from position I to position III (by passing through 0).

It will also be noticed that, in the present invention, and for at least a part of the rack (for the T_m section in the example described) the foot p can move according to the case, on the right or on the left of N_1 . The right side and the left side communicate through the space i situated between the two sections T_m and T_v . The right way corresponds to the descent to position III, whereas the left way enables the direct descent from the stopping position I to position IV (through the intermediary of the passage position 00), or from position III to position IV.

It is clear from the above specification that the guiding surfaces are all made of elements of planes, vertical or not, and inclined with respect to the rack, said elements being placed on one side of the rack or on the other side, part of these planes being connected to the other, and eventually connected to the rack, said planes ensuring according to the case, the change of direction of the foot p , and/or its motion up-or down, by resting or skidding.

In addition to the manoeuvring facilities which have been referred to, the slide in accordance with the invention, also possesses the following advantage:

By comparing this slide with that shown in Fig. 1, we see that the longitudinal guiding cheek along the slide g is eliminated.

This suppression is important. For in the case of the prior system of Fig. 1, if the foot p has jumped out of the trough (due to the lateral impact from pieces of wood carried along the water), the foot p cannot reach the pit G , when the flashboard is lowered. If the foot p is not in G , when the flashboard is lying it means that it is impossible for it, to fork the rack, when the flashboard is being raised, and therefore cannot engage with one of the teeth d_1 , d_2 and d_3 .

In that case, the help of a diver, may be necessary to put back the foot into the correct position.

With the new slide, the foot always reaches the pit G , when the flashboard is lowered. A precise location in this pit is without significance, for it is in any cases, the leaving position IV in Fig. 7.

The slide in accordance with the invention therefore affords great safety when employed.

It is obvious that the invention is not restricted to the example described and that all kinds of modifications can be applied to the various guiding surfaces, as regards their number, their shape and arrangement, without going outside the scope of the present invention.

In particular, it would be possible, by employing more complicated shapes, but keeping to the combination of inclined planes described above, to perform the following direct passages, in addition to the two direct passages from III to IV and I to III:

From I to II, which would necessitate, up-stream from I, the utilising of a new passage position which be added to the positions 6 and 00 mentioned above.

From II to III, which would lead to interrupting the rack between II and I, as occurs between III and II, in accordance with the aforementioned description.

However, the last two passages would not, in a general way, be of much interest on Aubert flashboard dams, so that the corresponding increase in the price of the slide would not be warranted.

I claim:

1. A dam flashboard controlling slide comprising a strut pivotally connected at one end to the down-stream side of said flashboard upon a horizontal axis and with lateral play therebetween, a foot carried by the other end of said strut, a rack having at least two spaced apart sections for at times guiding the foot of said strut during the pivoting of said flashboard with both sections extending substantially perpendicular to the axis of pivoting of said strut, each section of said rack having at least one tooth provided thereon for at times receiving and retaining the foot of said strut against down-stream movement, the up-stream section of said rack having a vertically inclined profile portion for laterally displacing the foot of said strut, when slid therealong, from said rack, means provided with said rack for guiding said foot across said up-stream section when so displaced therefrom upon up-stream movement of said foot, the down-stream section of said rack having profile portions inclined vertically and longitudinally of said rack for directing the elevation and lateral displacement of said

5

strut foot onto said down-stream section upon being slid therealong when displaced from said up-stream rack section, and guiding means for directing said strut foot towards the ends of said rack sections when displaced therefrom upon movement of said foot longitudinally of said rack.

2. A dam flashboard controlling slide as claimed in claim 1, wherein said rack sections consist of a pair of vertical ribs having downwardly curved end portions for guiding said strut foot thereon upon up-stream movement of said foot, said ribs being spaced apart providing a passageway for said foot, said guiding means including vertical ribs extending on acute angles relative to said rack sections for guiding said strut foot from one rack section to the other rack section when displaced from said rack.

3. A dam flashboard controlling slide as claimed in claim 1, wherein said down-stream section profiled portions include a downwardly curved rib-shaped portion extending up-stream between said up-stream section and a portion of said guiding means, a lateral portion having dihedral surfaces one sloping up-stream and the other towards its rib and a dihedral passageway provided between said section and its rib and said first mentioned dihedral surfaces whereby said strut foot is guided onto said down-stream section upon down-stream movement of said foot.
